LOW PRESSURE DROP FRACTIONATING TRAY**Vernon O. Bowles, Rye, N.Y., assignor to Socony Mobil Oil Company, Inc., a corporation of New York****Application July 5, 1955, Serial No. 519,839****8 Claims. (Cl. 261—114)**

The present invention relates to an improvement in fractionating towers and particularly to the trays used therein in which a gas passes through a liquid. This application is a continuation-in-part of my co-pending application Serial No. 326,481, filed December 17, 1952, and issued as U.S. 2,714,504 on August 2, 1955, which, in turn, is a continuation-in-part of my application Serial No. 186,860, filed September 26, 1950, and issued as U.S. 2,692,128 on October 19, 1954.

Fractionating towers of the type widely employed in the refining industries for fractionating hydrocarbon liquids and the like have heretofore generally been constructed by mounting a plurality of rigid horizontal plates at various elevations within a cylindrical tank. These horizontal plates are ordinarily pierced by a plurality of orifices over which are placed bubble caps so that vapors rising in the tower pass up through the orifices and bubble down into the liquid on the plate. The downwardly flowing liquid passes from plate to plate by means of down-comers to afford contact between vapor and liquid at a number of various levels as determined by the relative position of the horizontal plates or bubble trays.

The trays of the bubble cap type of tower are usually constructed of metal and supported by annular flanges spaced along the outer edge of the trays and secured to the inside wall of the tank. To afford the necessary rigidity and strength, the trays must be constructed of relatively thick metal plate and must frequently have supporting beams to avoid deflection of the plate. As generally recognized, the maintenance, and particularly the cleaning, of bubble cap type trays is cumbersome. It is, for example, well known that, during fractionation of petroleum hydrocarbons, a gummy or carbonaceous deposition frequently takes place on the plates due to polymerization, coking, and the action of sulfur compounds and other agents. The cleaning of bubble cap plates made up of numerous bubble caps, risers, and associated fastenings in such instances is a tedious operation, accomplished only at the expenditure of considerable time and labor. Furthermore, while the trays are preferably constructed of a corrosion-resistant metal such as stainless steel, the cost of fabricating a tray of such material having sufficient thickness, together with supporting beams to provide the necessary rigidity and strength, has heretofore been an expensive proposition. Common practice has been to construct trays of less expensive material such as cast iron and, more recently, steel. A tray fabricated from such metals affords the necessary thickness in construction at a comparatively reasonable cost but such trays are heavy and are unsatisfactory when liquid and vapors coming in contact therewith are of a corrosive nature. Corrosion of the trays necessitates frequent replacement or repair thereof which, as pointed out hereinabove, is not only an expensive proposition but a laborious and time-consuming operation due to the complexity of design and to the weight of the heavy metal parts used in fabrication. Thus, economics often dictate that the fractionating tray be con-

structed of corrosion-resistant alloy regardless of initial cost.

In my aforementioned co-pending application Serial No. 326,481, issued as U.S. 2,714,504 on August 2, 1955, there is described a lightweight fractionating tray designed to overcome the above disadvantages in fractionating tray construction and to provide a fractionating tower wherein a corrosion-resistant metal can be employed in relatively thin sections for fabrication of the tray. The functional members making up such tray serve as lightweight structural beams extending transversely across the tank and afford construction of a comparatively light tray which is easy to fabricate, assemble, and maintain in operation.

It has been established by commercial use of the latter tray construction that the same is more economical to install and maintain in operation than other types of commercially available fractionating trays. In addition, it has been found that such tray is highly effective in accomplishing the desired fractionation. It has been observed, however, with utilization of these trays under conditions of extremely low pressure drop, such as desired in a vacuum fractionation system, that back-flow of liquid through the inlet vapor sections of the trays is sometimes encountered. Such liquid back-flow has been particularly prevalent under conditions of low or partial submergence of the slots or serrations, i.e., where the top of the same is actually at an elevation higher than the top of the riser. Under such conditions, maintained to secure the desired low pressure drop, if vapor does not flow through the slots or serrations, liquid is bound to back-flow. As will be evident, back-flow of liquid in the inlet tray section is undesirable since the efficiency of the fractionating tower is thereby greatly diminished because only a portion of the liquid is being contacted.

It is accordingly the major object of the present invention to eliminate back-flow of liquid through the inlet vapor sections of trays using the above type of design, while retaining the advantages of economy and inherent structural strength of such tray construction.

A further object is the provision of means for activating the inlet upstream vapor section of a tray of the type described in co-pending application Serial No. 326,481, issued as U.S. 2,714,504 on August 2, 1955, when the same is used under conditions of low pressure drop.

A fractionating tray construction designed to fulfill the aforesaid objects is hereinafter described, together with other features of the invention.

The invention will be more readily understood by reference to the accompanying drawings wherein:

Figure 1 is an elevational view partly in section of a portion of a fractionating tower showing trays constructed in accordance with one embodiment of the invention.

Figure 2 is a plan view of a fractionating tray embodying one form of the invention.

Figure 3 is an isometric view of a fractionating tray fabricated in accordance with the invention.

Figure 4 is a detailed side isometric view showing one means of interlocking of the inlet vapor section of the tray with an adjacent section.

Figure 5 is a detailed side isometric view showing an alternate means of interlocking of the inlet vapor section of the tray with an adjacent section.

Figure 6 is an enlarged isometric view of the inlet vapor section of the fractionating tray showing one embodiment of the invention.

Figure 7 is an enlarged isometric view similar to Figure 6 but illustrating an alternate means for activation of the inlet vapor section.

Figure 8 is an enlarged isometric view similar to Figure 6 but illustrating another alternate means for activation of the inlet vapor section.

Figure 9 is an enlarged isometric view similar to Fig-

ure 6 but illustrating still another means for activation of the inlet vapor section.

Figure 10 is an enlarged isometric view similar to Figure 6 but showing another alternate embodiment for activating the inlet vapor section.

Referring more particularly to the drawings, in which like reference characters denote like parts, 1 designates an elongated cylindrical tank which forms the shell of the fractionating tower. Since the tank may be of any desired height and diameter, only a portion thereof is shown. A plurality of trays are mounted at various elevations throughout the tank, the number of said trays depending upon the requirements of the fractionation to be performed. While only two trays have been shown in Figure 1, it will be understood that additional trays may be positioned above and below the particular set of trays illustrated. A plurality of support rings 2 are welded or otherwise secured to the inside wall of tank 1. Resting upon and affixed to each support ring are the members which make up the fractionating tray. Adjacent to each group of horizontal trays are downcomers 3 through which liquid passes. Each downcomer is sealed by the level of liquid on the tray below, thus preventing the upward passage of vapors therethrough.

The fractionating trays, as will be seen, are composed of a series of troughs 4 spaced at uniform intervals transversely across the tank and positioned in co-planar relationship one with the other. Each of the troughs is secured to the support ring 2 by suitable fastening means such as bolts 5 held in position by nuts 6. The vertical walls of each of the troughs are positioned at substantially right angles to the respective trough bottoms. However, said walls may vary from the vertical as much as 30° without affecting the functional property thereof, it being understood that the individual troughs in a given tray are preferably of the same design. To each trough is attached an L-shaped section composed of a horizontal leg 7 attached to the downstream edge of the trough and a vertical leg 8, the lower edge of which is serrated. The aforementioned L-shaped section overhangs into the next succeeding trough, thereby providing a passage 9 between each pair of adjacent troughs. The L-shaped section overhanging the upstream trough of each tray is attached to a vertical plate 10 which, in turn, is affixed by suitable fastening means, such as bolts 11, to angle support plate 12, the horizontal extension of the latter being contiguous with and affixed to support ring 2 by bolts 13. The downstream wall of the trough terminating each tray section is affixed by bolts 14 to plate 15, which extends vertically below the horizontal level of said trough to a point sufficient to effect an adequate vapor seal. This may be accomplished by extending plate 15 downwardly to a point sufficiently above plate 12 of the next lower tray so that liquid can easily flow thereunder but sufficiently below the top of vertical plate 10 of said lower tray to provide a vapor seal. When the liquid flow is very large, plate 10 is desirably vertically extended to provide an adequate vapor seal. Alternatively, a weir 19 may be vertically extended to provide the vapor seal. Access between trays for maintenance or repair can be obtained by simply removing a few tray sections. For such purpose, it is desirable to facilitate vertical entry through the tray sections by providing alternate trays with a removable L-shaped section 16 which is fastened by bolt 17 or other suitable means to plate 18. Access into the tray section when desired can be gained by effecting removal of section 16 and the remaining downstream troughs making up the tray. An appropriate number of the upstream troughs of the next lower tray can then easily be removed and likewise alternate groups of downstream and upstream troughs of succeeding levels of trays may be removed until the desired point of entry is attained.

The downcomers are staggered on alternate trays in such manner as to cause a back-and-forth travel of liquid in a horizontal direction across each successive tray in

addition to the vertical flow from tray to tray. The horizontal flow of liquid across each tray is caused by vapor impact compensating for the hydraulic gradient between the point where liquid enters the tray and the point where it leaves the tray.

Thus, the vapors being contacted issue in the same direction as liquid flow across the tray and the impinging action of the vapors serves to move the liquid across each tray and thereby compensates for the hydraulic gradient. 10 The design is such, however, that the liquid is not too rapidly accelerated across the tray with undesirable reduction in contacting efficiency. The vertical plate 10 of each tray is affixed through plate 12 to support ring 2 in such manner that it is substantially perpendicular to the flow of liquid proceeding across each tray after the same has entered the tray through downcomer 3. Likewise, since the vertical walls of each of the L-shaped sections are parallel to the vertical plate 10, these members are also located perpendicularly to the horizontal flow of liquid across the tray. The result of this perpendicular arrangement of troughs and overhanging L-shaped sections to the line of liquid flow is a rippling effect as the liquid travels across each tray and passes downwardly through the tank. The combination of the rippling effect 20 of the liquid and the bubbling action of the vapors passing therethrough thus affords an intimate degree of contact between vapor and liquid and so compensates for the hydraulic gradient required to effect horizontal liquid flow that a high degree of contacting efficiency is attained.

Referring to the plan view of the fractionating tray shown in Figure 2, it will be seen that the troughs 4 and overhanging L-shaped sections made up of legs 7 and 8 extend transversely across tank 1 and are suitably stiffened by one or more webs 21. These plate-like metal strips extend across the trough section of the tray in a right angle direction to the troughs and serve to stiffen the vertical walls of the trough section against deflection, particularly in the central portion of the tray. Any desired number of stiffening webs may be employed. They are, however, generally positioned on approximately 12 to 30-inch centers. The webs are slotted so that the serrated edge of overhanging vertical leg 8 interfits into the slot provided and thereby serves to impart structural strength to the fractionating tray. The slot in web 21 is shown particularly in Figure 4 and is denoted as 29. While the aforementioned stiffening webs are not generally necessary in trays of small diameter, they have been found to greatly improve the overall structural strength of the trays and their use is therefore preferred.

50 The area encompassed by the overhanging L-shaped sections and the vertical trough walls to which said sections are attached is fitted with end closure plates 22, as particularly shown in Figure 4, the ends of the troughs in such embodiment remaining open. End closure plates 55 22 are perpendicularly affixed by welding or other suitable means to the L-shaped sections and the vertical trough walls to which said sections are attached to provide a satisfactory end closure of such area. These end plates are slotted and their lowermost edges are flush 60 with support ring 2. The small clearance between the shell of tank 1 and the end closure plates may, if desired, be filled with packing, although the use of packing is not considered essential and is not generally practiced commercially.

65 Alternatively, the troughs and overhanging L-shaped sections making up the trays may be fitted with end closure plates as described in application Serial No. 326,481, issued as U.S. 2,714,504 on August 2, 1955, or end closure may be effected by a plurality of angular plates as 70 described in detail in Patent No. 2,699,929. Such means of end closure is shown in Figure 5. Referring to this figure, end closure of the area encompassed by the overhanging L-shaped sections and the vertical trough walls to which said sections are attached is effected by plates 75 30 and 31. These plates are angular in form, one wall

thereof serving to effect end closure of a designated portion of the aforesaid area and the other wall thereof being contiguous with and affixed to the upstream wall of the adjacent downstream trough. The angle between walls comprising said plates may be substantially a right angle or may, depending upon the contour of the members making up the tray of which it is desired to effect end closure, vary from a right angle by as much as 45°. Plates 30 and 31 are attached by spot welding or by suitable fastening means, such as bolts 32 and nuts 33, to the adjacent upstream trough wall with which these plates are contiguous. The walls of the plates which are contiguous with the adjacent upstream trough wall, as well as said wall, are pierced by openings through which said bolts pass and are affixed, serving to impart structural strength to the arranged members. Plate 31, which serves to effect closure of the space between overhanging leg 8 of the L-shaped section and the upstream wall of the adjacent and interlocking downstream trough, is preferably provided with a tab 34 which is substantially perpendicular to the end closure wall of these plates and contiguous with leg 7 of the aforesaid overhanging L-shaped section. Tabs 34 are affixed to legs 7 by suitable means, for example, bolts 35 and nuts 36. It is to be realized that end closure plates 31 will function without top tabs 34. Generally, however, it is desirable to employ tabs on end closure plates 31 since the same further serve to impart structural strength to the overall arrangement of interlocking troughs.

The invention as set forth hereinabove is particularly directed to activation of the inlet vapor sections of the trays to eliminate back-flow of liquid therethrough. Back-flow has been found to be the result of insufficient gasification of the liquid phase in the initial trough with the result that density of the liquid therein is greater than that contained in subsequent trough and gases are thus prevented from flowing through the serrations or slots entering this section. It accordingly becomes necessary to gasify liquid in the initial trough sufficiently so that the density thereof will be no greater than the density of liquid in subsequent downstream troughs and therefore the tendency toward back-flowing will be eliminated.

Such is accomplished in accordance with the present invention by providing means for effecting the drawing of liquid away from the vertical leg of the initial upstream L-shaped section above the serrations therein to an extent sufficient to prevent submergence of said serrations by liquid flowing over the horizontal leg of the initial upstream L-shaped section, down the vertical leg thereof and into the adjacent trough. Referring to Figures 1—6 of the drawing, activation of the inlet vapor section is brought about by affixing to the horizontal leg 7 of the initial upstream L-shaped section overhanging the adjacent trough of each tray a weir 19. This weir may be affixed by suitable means such as by welding, bolting, or the like. Weir 19 should suitably be of such height that liquid, instead of flowing over the horizontal leg of the initial upstream L-shaped section and down the vertical leg of such section above the serrations therein is forced to flow over the weir edge under conditions such that a vapor space exists between the downstream face of the weir and the stream of liquid flowing thereover as is usually observed with sharp edged weirs. The upper part of the serrations thus becomes free to act and once the action is initiated, the typical turbulence is set up and the entire vapor section and trough become activated.

An isometric view of the fractionating tray of the type described herein is illustrated by Figure 3. The vertical leg 8 of the overhanging section is serrated with the serrations 20 pointing downward and extending into the adjacent downstream trough to provide an effective bubbling means for passing vapor through liquid flowing perpendicularly across the trough. It will further be noted that slotted stiffening webs 21 interfit into and engage the serrated edges of the overhanging sections. Dur-

ing operation, vapors from the tray below pass up through passage 9 between two adjacent troughs over the upstream edge of the downstream trough and then through the serrated edge of leg 8 where vapor bubbles are released into the liquid on this trough. Downflowing liquid enters the tray through downcomer 3 and flows over the roof of the inlet vapor section, coming in contact with weir 19 and flowing over said weir into the adjoining trough and thereafter proceeding across the tray section.

The arrangement of end closure plate 22 and weir 19 is shown in detail by the isometric view of Figure 6. The characteristic of the weir 19, even at very low liquid flow, is that a vapor space exists between the downstream face of the weir and the stream of liquid flowing thereover. The upper portion of the serrated edges of leg 8 is accordingly free to act and once the action is initiated the typical turbulence is set up and the entire vapor section and trough become activated. The plate, as shown in the arrangement of Figure 4 for one of the troughs, is provided with a slot 23 which extends vertically from the lower edge of the end plate at a point corresponding to the juncture of the upstream wall of the adjacent downstream trough and the end closure plate. Such slot interfits over the vertical edge of the adjacent downstream trough.

An alternate provision of means for activating the inlet vapor section of the tray is shown in Figure 7. Referring more particularly to this figure, it will be seen that the roof of the inlet vapor section, i.e., horizontal leg 7, is provided with a row of perforations or openings 24. Over these openings is positioned a deflecting bar 25. This embodiment results in a small stream of vapor or vapor bubbles flowing along the roof of the inlet vapor section downstream of the point of introduction with the result that at a number of localized points the liquid is pulled away from the vertical face of the vapor section, i.e. vertical leg 8, above the serrated edge thereof and bubbling is initiated. Once the bubbling is initiated, typical turbulent action starts and the density of liquid in the trough is reduced with the result that back-flow is minimized or entirely eliminated even though the top of the riser, i.e., the upstream edge of the adjacent downstream trough, does not extend as high as the root of the serrations in vertical leg 8.

In Figure 8, another alternate means for activating the inlet vapor section is shown. In this modification the roof of the inlet vapor section, i.e., horizontal leg 7, is provided with a horizontal extension 26 jutting a small distance beyond the vertical leg 8, overlying and being substantially horizontal to the bottom of the adjacent trough.

In Figure 9 is shown still another alternate means for activating the inlet vapor section. In this modification, the desired activation is brought about by means of a plurality of elongated openings 27 extending from the roots of the serrations in leg 8 vertically upward to the roof of the inlet vapor section. In this embodiment, it is contemplated that the desired activation may be attained with elongated openings on every other or perhaps even on every third one of the slots. Utilizing this modification, activation is initiated because of vapor issuance from the top of the elongated openings. This vapor issuance breaks up the action of the liquid tending to cling to the face of vertical leg 8 and allows bubbling action by the main part of the serrated edge thereof to proceed with consequent reduction in liquid density in the initial trough.

In Figure 10 is shown still another alternate means for bringing about the desired activation of the inlet vapor section. In this embodiment, a plurality of openings 28 are provided in the vertical serrated leg 8 of the inlet vapor section at a point above the level of the roots of the slots or serrations. Activation utilizing this embodiment would take place in a manner similar to that achieved with the embodiment shown in Figure 9. That

is, activation is initiated because of vapor issuance from the openings 28. This vapor issuance breaks up the action of the liquid tending to cling to the face of vertical leg 8 and allows bubbling action by the main part of the serrated edge thereof to proceed with consequent reduction in liquid density in the initial trough.

The width of the troughs 4 is directly related to the slot area, i.e., the area of all of the slots in a given tray. Preferred design employs slot area equal to about 8 to about 15 percent of the total tower cross section. However, the width of the troughs making up the instant trays may be so established as to obtain slot areas ranging from about 5 to about 20 percent of the total tower cross section. An advantage of the present tray construction is the high percentage of riser area attained, i.e., the cross sectional area between the troughs 4 through which the vapors pass upwardly. Existing bubble cap trays achieve riser areas ranging from 6 to 15 percent, whereas the instantly described tray may achieve a riser area of 25 to 30 percent. Moreover, the tray construction of the invention has a comparatively high reversal area and vapor downflow area corresponding to the annular area in existing bubble cap tray design. These large areas which the trays of this invention thus afford result in low pressure drop of vapor flow through the tray, which is particularly advantageous in vacuum fractionation. Under conditions of extremely low pressure drop, back-flow of liquid in the inlet vapor section of the tray is prevented in accordance with the present invention by reduction of the density of liquid in the initial upstream trough section by induced gasification thereof. Such gasification may be accomplished by the provision of means for the drawing of liquid away from the vertical face of the vapor section above the slots sufficiently so that these slots do not become submerged by the liquid flowing over the roof of the vapor section down the face of this section above the slots and into the trough. It is contemplated that any suitable means for effecting activation of the inlet vapor section may be employed. Of the various means shown in the attached figures, the embodiment illustrated in Figure 6 is preferred. It will, however, be realized that any of the other various modifications shown may likewise be effective in attaining the desired activation. It is also contemplated that a combination of two or more of the illustrated means for effecting the desired activation may be employed. Thus, for example, the means illustrated in Figures 6 and 7 may be employed. Likewise, the activating means shown in Figures 6 and 9 may be employed in combination as well as the means shown in Figures 6 and 10. It will thus be apparent that the present invention contemplates any suitable means for effecting activation of the inlet vapor section of the tray by reducing the density of liquid contained therein, whereby back-flow of liquid therethrough is prevented, resulting in an increased efficiency.

While there has been described various preferred embodiments of the present invention, it will be understood that the invention is not limited in scope to the specific details of construction illustrated and described but that the same is subject to considerable variation without departing from the underlying features of the invention as expressed in the claims set forth below.

I claim:

1. In a lightweight tray for use in a fractionating tower comprising a plurality of troughs spaced at uniform intervals transversely across the tower and arranged in co-planar relationship one with the other, a plurality of L-shaped sections having the horizontal legs thereof attached to one edge of each of the aforementioned troughs, the vertical legs of such sections being serrated and pointing downward and overhanging into adjacent troughs, thereby affording passages for the flow of vapor therethrough, a plurality of end closure plates affixed to either end of the troughs and overhanging sections, each of said plates being slotted and the slots therein engaging the

vertical wall of the next adjoining trough, a plurality of stiffening webs extending across the troughs in a right angle direction thereto, said stiffening webs being slotted and the slots therein engaging the serrated edges of said overhanging vertical legs, the improvement wherein the horizontal leg of the initial upstream L-shaped section is provided with a weir, protruding from the upper surface of said horizontal leg, whereby liquid after passage over said weir is subjected to gasification with accompanying reduction in density thereof and is drawn away from the vertical leg of said initial upstream L-shaped section above the serrations therein to an extent sufficient to prevent submergence of said serrations by flow of said liquid into the adjacent downstream trough.

2. In a lightweight tray for use in a fractionating tower comprising a plurality of troughs spaced at uniform intervals transversely across the tower and arranged in co-planar relationship one with the other, a plurality of L-shaped sections having the horizontal legs thereof attached to one edge of each of the aforementioned troughs, the vertical legs of said sections being serrated and pointing downward and overhanging into adjacent troughs, thereby providing passages for the flow of vapor therethrough, a plurality of angular plates, the walls of which respectively effect end closure of space between downstream trough walls and adjacent upstream trough walls and afford support to upstream walls by being contiguous therewith and affixed thereto and a second plurality of angular plates, the walls of which respectively effect end closure of space between upstream trough walls and adjacent vertical legs of said overhanging sections and afford support to said upstream walls by being contiguous therewith and affixed thereto, the improvement wherein the horizontal leg of the initial upstream L-shaped section is provided with a weir, protruding from the upper surface of said horizontal leg, whereby liquid after passage over said weir is subjected to gasification with accompanying reduction in density thereof and is drawn away from the vertical leg of said initial upstream L-shaped section above the serrations therein to an extent sufficient to prevent submergence of said serrations by flow of said liquid into the adjacent downstream trough.

3. In a fractionating tower comprising an elongated tank, a plurality of support rings affixed at various elevations to the inner periphery of said tank, a plurality of troughs arranged in co-planar relationship upon said support rings and extending transversely across the tank, a plurality of end closure plates, one of which is affixed to either end of said troughs, said end plates being slotted and the slots therein engaging the vertical walls of adjacent troughs to rigidly hold said troughs in interlocking arrangement on said support rings perpendicular to the line of liquid flow across said tank, a plurality of L-shaped sections having the horizontal legs thereof attached to one edge of each of said troughs, the vertical legs of said sections pointing downward, being serrated and overhanging into adjacent troughs to thereby afford passages for upward vapor flow through said tank, the improvement which comprises providing the horizontal leg of the initial upstream L-shaped section with a weir, protruding from the upper surface of said horizontal leg, whereby liquid after passage over said weir is subjected to gasification with accompanying reduction in density thereof and is drawn away from the vertical leg of said initial upstream L-shaped section above the serrations therein to an extent sufficient to prevent submergence of said serrations by flow of said liquid into the adjacent downstream trough.

4. In a lightweight tray for use in a fractionating tower comprising a plurality of troughs spaced at uniform intervals transversely across the tower and arranged in co-planar relationship one with the other, a plurality of L-shaped sections having the horizontal legs thereof attached to one edge of each of the aforementioned troughs, the vertical legs of said sections being serrated and point-

ing downward and overhanging into adjacent troughs, thereby affording passages for the flow of vapor therethrough, a plurality of end closure plates affixed to either end of the overhanging sections and the vertical trough walls to which said sections are attached, each of said plates being slotted and the slots therein engaging the vertical wall of the next adjoining trough, the improvement wherein the horizontal leg of the initial upstream L-shaped section is provided with a weir, extending vertically from said horizontal leg and contiguous with the vertical leg of said initial upstream L-shaped section, whereby liquid passing over said weir is subjected to gasification with accompanying reduction in density thereof and is drawn away from the vertical leg of said initial upstream L-shaped section above the serrations therein to an extent such that a vapor space exists between the downstream face of the weir and the stream of liquid flowing thereover and sufficient to prevent submergence of said serrations by flow of said liquid into the adjacent downstream trough.

5. In a lightweight tray for use in a fractionating tower comprising a plurality of troughs spaced at uniform intervals transversely across the tower and arranged in co-planar relationship one with the other, a plurality of L-shaped sections having the horizontal legs thereof attached to one edge of each of the aforementioned troughs, the vertical legs of said sections being serrated and pointing downward and overhanging into adjacent troughs, thereby affording passages for the flow of vapor therethrough, a plurality of end closure plates affixed to either end of the overhanging sections and the vertical trough walls to which said sections are attached, each of said plates being slotted and the slots therein engaging the vertical wall of the next adjoining trough, the improvement wherein the initial upstream L-shaped section is provided with an extension jutting from the horizontal leg thereof overlying and substantially horizontal to the adjacent trough, whereby liquid after passage over said extension is subjected to gasification with accompanying reduction in density thereof and is drawn away from the vertical leg of said initial upstream L-shaped section above the serrations therein to an extent sufficient to prevent submergence of said serrations by flow of said liquid into the adjacent downstream trough.

6. In a light weight tray for use in a fractionating tower comprising a plurality of troughs spaced at uniform intervals transversely across the tower and arranged in co-planar relationship one with the other, a plurality of L-shaped sections having the horizontal legs thereof attached to one edge of each of the aforementioned troughs, the vertical legs of said sections being serrated and pointing downward and overhanging into adjacent troughs, thereby affording passages for the flow of vapor therethrough, and a plurality of elements affixed to either end of the overhanging sections and the vertical trough walls to which said sections are attached adapted to interlock adjacent troughs with attached sections one into the other, the improvement wherein the horizontal leg of the initial upstream L-shaped section is provided with a weir, protruding from the upper surface of said horizontal leg, whereby liquid after passage over said weir is subjected to gasification with accompanying reduction in density thereof and is drawn away from the vertical leg of said initial upstream L-shaped section above the serrations therein to an extent sufficient to prevent submergence of said serrations by flow of said liquid into the adjacent downstream trough.

7. In a light weight tray for use in a fractionating tower comprising a plurality of troughs spaced at uniform intervals transversely across the tower and arranged in co-planar relationship one with the other, a plurality of L-shaped sections having the horizontal legs thereof attached to one edge of each of the aforementioned troughs, the vertical legs of said sections being serrated and pointing downward and overhanging into adjacent troughs, thereby affording passages for the flow of vapor therethrough, and a plurality of elements affixed to either end of the overhanging sections and the vertical trough walls to which said sections are attached adapted to interlock adjacent troughs with attached sections one into the other, the improvement wherein the horizontal leg of the initial upstream L-shaped section is provided with a weir, extending vertically from said horizontal leg and contiguous with the vertical leg of said initial upstream L-shaped section, whereby liquid passing over said weir is subjected to gasification with accompanying reduction in density thereof and is drawn away from the vertical leg of said initial upstream L-shaped section above the serrations therein to an extent such that a vapor space exists between the downstream face of the weir and the stream of liquid flowing thereover and sufficient to prevent submergence of said serrations by flow of said liquid into the adjacent downstream trough.
8. In a light weight tray for use in a fractionating tower comprising a plurality of troughs spaced at uniform intervals transversely across the tower and arranged in co-planar relationship one with the other, a plurality of L-shaped sections having the horizontal legs thereof attached to one edge of each of the aforementioned troughs, the vertical legs of said sections being serrated and pointing downward and overhanging into adjacent troughs, thereby affording passages for the flow of vapor therethrough, and a plurality of elements affixed to either end of the overhanging sections and the vertical trough walls to which said sections are attached adapted to interlock adjacent troughs with attached sections one into the other, the improvement wherein the initial upstream L-shaped sections is provided with an extension jutting from the horizontal leg thereof overlying and substantially horizontal to the adjacent trough, whereby liquid after passage over said extension is subjected to gasification with accompanying reduction in density thereof and is drawn away from the vertical leg of said initial upstream L-shaped section above the serrations therein to an extent sufficient to prevent submergence of said serrations by flow of said liquid into the adjacent downstream trough.
